(57) **CLAIM**

The ornamental design for a rear table, as shown and described.

DESCRIPTION

FIG. 1 is a front, right, and top perspective view of a rear table, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right, and top perspective view of the rear table of FIG. 1 when a bracket of the rear table is open. The broken lines shown in the drawings are included for the purpose of illustrating portions of the rear table that form no part of the claimed design.
